UNITED STATES PATENT OFFICE.

LYMAN MIDDLEDITCH, OF NEW YORK, N. Y.

PLATE-CLAMP.

1,164,954.

Specification of Letters Patent. Patented Dec. 21, 1915.

Application filed April 29, 1913. Serial No. 764,320.

To all whom it may concern:

Be it known that I, LYMAN MIDDLEDITCH, a citizen of the United States, and a resident of New York city, in the county of New York and State of New York, have invented certain new and useful Improvements in Plate-Clamps, of which the following is a specification.

The present invention relates to a plate clamp of the type more particularly known as a "register hook" for printing machines, and has for its object simplicity of construction and the production of a propelling means for moving the clamp in the groove of the plate carrying member which will not be adversely affected when clogged by ink.

The invention consists of the features set forth in the accompanying claims, a preferred embodiment of which is disclosed in the accompanying description and drawings.

In the said drawings: Figure 1 is a plan view of a plate carrying member with a plate clamped in position by means of clamps embodying the invention. Fig. 2 is a sectional view on the line 2-2 of Fig. 1. Fig. 3 is a detail sectional view on the line 3-3 of Fig. 1 with the plate removed. Fig. 4 is a plan view of the clamp with the parts in position to be dropped into the groove of the plate carrying member. Fig. 5 is a side elevation of Fig. 4. Fig. 6 is a view similar to Fig. 4 but with the parts in position to engage a plate. Fig. 7 is a vertical sectional view of the parts shown in Fig. 5. Fig. 8 is a sectional detail view showing the screw of the clamp in engagement with the threads of the groove.

Similar characters of reference indicate corresponding parts in the several views.

40 The plate carrying member may be either a cylinder, or, as here shown, a flat bed 10 provided with diagonally extending grooves 11 having oblique threads 12 on one side and provided with an undercut portion 13.

45 14 is the plate and 15 the plate clamp. The plate clamp consists in part of a supporting member 16 adapted to slide in the groove.

50 17 is a rotatable plate clamping member mounted in the supporting member 16 by means of the stem 18 provided, at its lower end, in line with the undercut portion 13, with a head 19 of a length substantially equal in one direction to the width of the groove 11, and long enough in the other direction to extend into the undercut portion 13 of the groove 11 and offset circumferen-

tially with relation to the clamping member 17 as shown. Thus the plate clamping member 17 and head 19 can be turned in unison.

When it is desired to place the clamp in the groove the member 17 is turned into the position shown in Fig. 4, which brings the head 19 into line with the supporting member, and after the clamp is placed in the groove, the member 17 is turned a part of a revolution, say 45°, in either direction, whereby the said member 17 is brought into position to clamp the plate and the head 19 is caused to extend into the undercut portion 13 as shown in Figs. 1, 3, 6 and 7.

The supporting member 16 further carries the rotatably and obliquely mounted screw 20 which is adapted to engage with the oblique threads 12. The shoulder 21 and pin 22 keep the screw 20 from movement lengthwise of its axis. When the member 17 is turned into the position shown in Fig. 6 one or the other of the two openings 23 will be over the screw 20 and will permit a wrench to be inserted in the socket 24 of the screw, which, when rotated, propels the supporting member along the groove 11. Should ink have accumulated in the threads 12, the rotation of the screw 20 will cut the caked ink out, and said ink will not prevent adjustment of the clamp. This is a great advantage over the usual gears employed in the teeth of which the ink accumulates and prevents the parts from moving.

When it is desired to insert the clamp into the groove, the member 17 is turned into the position shown in Fig. 4, as previously explained. Then the clamp can be inserted 95 into the groove by turning the screw 20 in a clockwise direction, or screw 20 and threads 12 can be engaged, and the screw slid downward to the right (Fig. 8). The member 17 is now given a 45° turn so as to bring the head 19 into the undercut portion 13. The screw 20 can then be rotated to slide the clamp along the groove.

What is claimed, is:

1. A plate carrying member having a groove provided with an undercut portion, a plate clamp comprising a supporting member adapted to be engaged in the groove, and a rotatable plate clamping member having a head in line with the undercut portion of a length substantially equal in one direction to the width of the groove and long enough in the other direction to extend into the undercut portion of the groove, whereby

when the plate clamping member is turned into position to engage the plate the head will extend into the undercut portion of the groove, and when the plate clamping member is turned into position to disengage the plate the said head will be out of the undercut portion and wholly within the groove.

2. A plate carrying member having a groove provided with an undercut portion, 10 a plate clamp comprising a supporting member adapted to be engaged in the groove, and a rotatable plate clamping member having a head in line with the undercut portion and rotatable in unison with the plate clamping member, whereby a partial revolution of the 15 plate clamping member will cause the head to extend into the undercut portion of the groove.

3. A plate carrying member having a 20 groove provided with an undercut portion, a plate clamp comprising a supporting member adapted to be engaged in the groove, and a rotatable plate clamping member having a head in line with the undercut portion and rotatable in unison with the plate 25 clamping member, and means for propelling the supporting member in the groove.

4. A plate carrying member having a 30 groove provided with threads on one side, a plate clamp, and a screw rotatably and obliquely mounted in said plate clamp and engaging with said threads.

5. A plate carrying member having a 35 groove provided with threads on one side, a plate clamp comprising, a supporting member, a plate clamping member rotatably engaged in the supporting member, and a screw rotatably and obliquely mounted in said supporting member and engaging with 40 said threads.

6. A plate carrying member having a groove provided with threads on one side and with an undercut portion below said groove, a plate clamp comprising, a supporting member adapted to slide in the groove, a rotatable plate clamping member having a head in line with the undercut portion and rotatable in unison with the plate clamping member, and a screw rotatably and obliquely mounted in said supporting member and engaging with said threads.

7. A plate carrying member having a 45 groove provided with straight oblique threads, a plate clamp, a screw rotatably and obliquely mounted in said plate clamp adapted to engage said threads, and means for preventing movement of the screw lengthwise of its axis.

8. A plate carrying member having a 50 groove provided with an undercut portion, a plate clamp comprising a supporting member adapted to be engaged in the groove, and a rotatable plate clamping member having

a head in line with the undercut portion of a length substantially equal in one direction 65 to the width of the groove and long enough in the other direction to extend into the undercut portion of the groove, whereby when the plate clamping member is turned into position to engage the plate the head will 70 extend into the undercut portion of the groove and when the plate clamping member is turned in position to disengage the plate the said head will be out of the undercut portion and wholly within the groove. 75

9. A plate carrying member having a groove provided with an undercut portion, a plate clamp comprising a supporting member adapted to be engaged in the groove, and a rotatable plate clamping member having a head in line with the undercut portion and rotatable in unison with the plate clamping member, whereby a partial revolution of the plate clamping member will cause the head to extend into the undercut- 85 portion of the groove.

10. A plate carrying member having a groove provided with an undercut portion, a plate clamp comprising a supporting member adapted to be engaged in the groove, and 90 a rotatable plate clamping member having a head in line with the undercut portion and rotatable in unison with the plate clamping member, and means for propelling the supporting member in the groove. 95

11. A plate carrying member having a groove provided with threads on one side and with an undercut portion below said groove, a plate clamp comprising a supporting member adapted to slide in the groove, a 100 rotatable plate clamping member having a head in line with the undercut portion and rotatable in unison with the plate clamping member, and a screw rotatable and completely mounted in said supporting member 105 and engaging with said threads.

12. A plate carrying member having a groove provided with an undercut portion, a plate clamp comprising a supporting member adapted to be engaged in the groove, a 110 rotatable member mounted in said supporting member, a plate clamping member at one end of said rotatable member, and a head in line with the undercut portion and of a length substantially equal in one direction 115 to the width of the groove and long enough in the other direction to extend into the undercut portion of the groove on the other end of said rotatable member.

Signed at New York city, in the county 120 of New York and State of New York this 26th day of April A. D. 1913.
